STEAM IRON

Albert C. Hoecker, St. Louis, Mo., assignor, by mesne assignments, to General Electric Company, New York, N. Y., a corporation of New York

Continuation of abandoned application Serial No. 292, January 2, 1948. This application May 24, 1954, Serial No. 431,917

4 Claims. (Cl. 38—77)

This invention relates to pressing irons, and particularly to pressing irons of the steam generating type adapted to discharge substantially dry steam, a mixture of steam and water, or atomized water.

This application is a continuation of my pending application Serial No. 292, filed January 2, 1948, for Steam and Dampening Iron, and, in general, represents improvements over the construction disclosed in my U. S. Patent No. 2,387,757, issued October 30, 1945.

The primary object of the invention is to provide a novel steam and dampening iron whereby dampening fluid can be conducted to the material being ironed, through the sole plate, and from above the sole plate.

Another object of the invention is to provide a novel steam and dampening iron with means whereby the particles of moisture or water from a dampening iron can be directed to the material being ironed without lifting the iron off the material.

It is another object of the invention to provide a steam and dampening iron with a control valve and an atomizing discharge outlet restricted to enable the steam pressure within the boiler to effect atomization of the dampening fluid discharged through said discharge outlet.

It is another object of the invention to provide a steam and dampening iron adapted to discharge substantially dry steam, a mixture of steam and water, or atomized water to the material to be ironed.

Other and further objects will appear in the specification and be specifically pointed out in the appended claims, reference being had to the accompanying drawings exemplifying the invention and in which:

Fig. 1 is a vertical central sectional view of the iron.

Fig. 2 is a top plan view of the iron.

Fig. 3 is a vertical sectional view taken on line 3—3 of Fig. 1.

Fig. 4 is a fragmentary bottom view of the sole plate.

Fig. 5 is a detail perspective view of the rear of the iron.

Figs. 6, 7, 8 and 9 are views of the valve showing the various open and closed positions thereof.

Referring by numerals to the accompanying drawings, 1 designates the iron generally. The iron includes a boiler 1' and a sole plate 2, said sole plate being cast as an integral part of the boiler. Between the lower wall 3 of the boiler and the sole plate is a recess 4 for the reception of a heating element 5. The heating element 5 is of conventional design and is provided with the usual terminals 6, said terminals being connected to a conductor 7 which conducts electrical energy from a source of supply to the heating element 5.

At the rear end of the boiler is a housing 12 cast as an integral part of the boiler walls for the reception of the terminals 6 of the heating element 5. In the lower wall 3 of the boiler which extends into the housing 12 are slots 9 for the reception of the terminals 6. Below the wall 3 and above the sole plate 2 is a slot 8 which communicates with the recess 4. The heating element

2

5 is inserted into the recess 4 through the slot 8 and the terminals 6 which are attached to the heating element are slidably inserted in the slots 9 for securing the heating element in position. A plate 10 is secured to the iron by screws 11 for closing the housing in which the terminals 6 are located, and in the plate 10 is an opening for the reception of the conductor 7.

The forward end of the sole plate 2 is provided with a steam distributing channel 13 having steam discharge outlets 14 to the under surface of the sole plate 2.

Extending up in the boiler is a steam distributing channel 15 which extends vertically and transversely of the iron, the walls of said channel being cast as an integral part of the boiler for conducting the steam through an opening in the sole plate and for conducting the steam through an opening 16 into the steam channel or chamber 13, from which the steam is conducted to the material to be ironed through the outlets 14 in the sole plate. The upper wall of the channel 15 is provided with an atomizing discharge outlet or spray slot 17 which communicates with the channel 15 and the boiler for conducting steam or atomized water to the material to be ironed.

This atomizing discharge outlet or spray slot 17 is very important because the small restricted outlet 17 retains sufficient steam pressure in the boiler to effect atomization of the water discharged therethrough.

Extending upwardly from the slot 17 and cast integral with the walls of the distributing channel 15 is a tubular member 18 which extends through the top wall of the boiler. On one side of the tubular member 18 and communicating therewith are a pair of water inlets 19 and 20 which in turn communicate with a water pipe 21 which extends into the water space in the boiler. Opposite the water inlets 19 and 20 is a water discharge outlet 22 which communicates with the discharge outlet or atomizing outlet 23 in the spray housing 24, and just below the outlet 22 is a steam inlet 25 which communicates with the tubular member 18.

Located within the tubular member 18 is a rotary valve 26, and extending through the valve is a passageway 27 which communicates with the water inlet 19 and the discharge outlet 22 and restricted atomizing discharge outlet 23 in the spray housing 24. Below the passageway 27 in the valve and extending through the valve is a second passageway 28 which communicates with the steam inlet 25 and the water inlet 20 and both of said inlets and the passageway 28 communicate with the discharge outlet 29 in the center of the valve and the atomizing discharge outlet 17, the discharge outlet 17 communicating with the distributing channel 15. The steam inlet 25 also communicates with a passageway 30 and discharge outlet 29 in the valve 26, the discharge outlet 29 communicating with the atomizing discharge outlet 17 in the channel 15. The operation of the valve 26 will be described later.

A valve stem 31 is secured to the valve 26 and extends through a stuffing box 32 and gland 33 and opening in the member 34 and is secured to the operating handle 35. The lower end of the member 34 is provided with an enlarged tapered portion 36 for sealing the tapered opening 37 in the boiler wall. The member 34 and tubular member 18 are provided with screw threads 38 for securing the member 34 in position.

The rear end of the boiler is provided with a cylindrical chamber 39, the wall of said chamber being cast integrally with the upper and rear walls of the boiler. The chamber communicates with the interior of the boiler 70 and the lower end of the chamber is reduced to form a valve seat 40 in which a valve 41 is seated. A valve stem 42 is secured to the valve 41, said stem extending

through a plate 43 and packing 44, said plate closing the upper opening in the chamber 39 and being secured to the boiler by screws 49. The upper end of the valve stem 42 is secured to an operating handle 45, said handle adapted to cooperate with a cam 46 which is cast as an integral part of the rear end of the boiler and extends transversely thereof for lifting the valve 41 off the seat 40. A spring 48 surrounds the valve stem 42 and engages the valve 41 and plate 43 for holding the valve on its seat. A bracket 50 on the handle 51, holds the packing 44 in position, said handle being secured to the iron by screws 52.

At the rear of the boiler and on the side of the chamber 39 is a box-like member or casing 56 including a funnel 55 which is cast integrally with the boiler wall and the wall of the housing 12 and in the wall of the chamber 39 and communicating with the box-like member and funnel 55 and chamber 39 is an opening or steam outlet 53 which communicates with a steam outlet 54 and between the outlets 53 and 54 and cast integrally with the walls of the box-like member 56 is a baffle 55'. This baffle 55' causes the steam to travel in zigzag manner around the baffle 55' in the casing or box-like member 56, before the steam is discharged through the opening 54 to the atmosphere, thereby reducing the steam pressure and preventing injury to the operator of the iron, in the event excessive steam pressure in the boiler should lift the valve 41 off the seat 40, or in the event the operator of the iron should accidentally lift the valve off its seat, while steam is in the boiler, for filling the boiler with water. The valve is lifted off the seat by moving the handle 45 from the low part of the cam 46 to the high part of the cam.

It will be noted that the valve 41 has a dual purpose: (1) it acts as a safety valve, and (2) it provides means for filling the boiler with water.

To prevent water entering the steam inlet 25 during the movements of the iron, the iron is provided with a baffle 57 which is cast integrally with the boiler and extends from the side walls of the boiler to the front of the boiler and in the baffle at the forward end thereof is a minute opening 58 which extends through the baffle in such a manner that any water passing through the opening will be discharged against the wall of the boiler and thereby prevent the water splashing upwardly into the steam inlet 25, and any water that may accidentally or otherwise pass through the opening 58 from the boiler will drain back into the boiler.

To operate the iron, it is only necessary to move the handle 45 to the high point on the cam 46 for introduction of water into the boiler through the funnel 55. After the boiler is filled with water to approximately one inch below the baffle 57, the handle 45 is moved to the low point on the cam 46. With the handle 45 at the low point of the cam 46, the boiler will be sealed and the valve 41 will act as a safety valve. The electric current may then be applied to the conductor 7 and the terminals 6 to heat the electric heating element 5 which will heat the sole plate 2 and the water in the boiler. After sufficient steam is generated and referring now to the enlarged valves shown in Figs. 6, 7, 8 and 9, it will be noted that in Fig. 7, the valve 26 is shown in closed position and the pointer on the handle 35 should point to (Off) on the dial on the handle 51. When the pointer on the handle 35 points to (Off) on the handle 51 no steam or dampening fluid will be conducted to the material to be ironed and the iron will act as a dry iron. If the operator of the iron desires a mixture of atomized steam and water the handle 35 is rotated clockwise until the pointer on the handle 35 points to (SW) on the handle 51. With the pointer on the handle 35 pointing to (SW) water will enter the passageway 28 in the valve 26 through the water inlet 20 and steam will enter the passageway 28 through the steam inlet 25 as clearly shown in Figs. 1, 3 and 6, mixing the steam and water

75 steam.

in the passageway 28. From the passageway 28 the mixed steam and water passes through the outlet 29 in the valve 26 and is discharged through the atomizing outlet 17 into the transverse opening 15 and from the transverse opening the mixture of atomized steam and water is conducted to the material to be ironed. Note the atomizing discharge outlet 17 extends up in the iron a distance from the material to be ironed so the atomized mixture of steam and water can scatter before contacting the material. Note also that the transverse opening 15 extends almost the full width of the iron and the atomizing discharge outlet extends parallel therewith, making it possible for the atomized mixture of steam and water to scatter over a considerable area of the material.

15 If the operator of the iron desires dampening the clothing or material with atomized water, the handle 35 is rotated until the pointer on the handle 35 points to (W) on the handle 51. With the pointer pointing to (W) water will enter the passageway 27 in the valve 26 through the water inlet 19 and be conducted to the material to be ironed through the outlet 22 and atomizing discharge outlet 23, as shown in Fig. 1 and in the enlarged valve view of Fig. 8. It will be noted that the atomizing discharge outlet 23 also extends above the sole plate so the atomized water can scatter before contacting the material to be ironed, thereby properly dampening the material.

20 If the operator of the iron desires steam only the handle 35 is rotated until the pointer on the handle 35 points to (S) on the handle 51. With the pointer on the handle 35 pointing to (S) on the handle 51 the valve will be in the position shown in the enlarged view of Fig. 9. With the valve open as shown in Fig. 9, steam will enter the valve passageway 30 through the steam inlet 25 and be conducted to the material to be ironed through the opening 29 in the valve and through the atomizing discharge outlet 17 and transverse opening. The transverse opening 15 extends through the sole plate 2 for conducting the steam to the material being ironed, however, while the iron is on the clothing or material part of the steam will enter the channel 13 through the opening 16 and be conducted to the material through the discharge outlets 14.

25 From the foregoing it will be noted that I have not only invented a steam iron but also a dampening iron that will dampen the material to be ironed sufficiently to remove wrinkles from all clothing, which is the most important part of the iron, since steam irons do not furnish sufficient moisture to remove wrinkles from all clothing.

30 Various modifications may be made in this invention without departing from the spirit thereof, and therefore the exact forms are to be taken as illustrative only, and not in a limiting sense and it is desired that only such limitations shall be placed thereon as necessitated in the prior art.

35 What I claim is:

1. A steam and dampening iron comprising a sole plate, a boiler for the reception of steam and water, said boiler having a steam space and a water space, an atomizing device comprising a water conductor having one end extending into said water space and the other end having an atomizing discharge outlet sufficiently restricted to retain sufficient steam pressure in said boiler to atomize the water passing through said discharge outlet, said discharge outlet extending above the sole plate exteriorly of said boiler, so the atomized water discharged from said outlet can scatter over a considerable area of the material being ironed without lifting the iron off the material, means communicating with the steam space in said boiler for conducting the steam through an opening in said sole plate to cause the steam to be forced through the material being ironed, and means for heating said sole plate and the water in said boiler to produce steam.

2. A steam and dampening iron comprising a sole plate, a boiler for the reception of steam and water, said boiler having a steam space and a water space, an atomizing device comprising a water conductor having one end extending into said water space and the other end of said conductor extending above said sole plate exteriorly of said boiler for conducting atomized water from said boiler to the material to be ironed so that the atomized water will scatter over the material to be ironed in a cloud of atomized water, at least a part of said conductor being restricted to retain sufficient steam pressure in said boiler to atomize the water passing through said conductor and a valve in the passageway of said conductor for controlling the water passing through said conductor, means communicating with said steam space and an opening through said sole plate for conducting steam to the material to be ironed, and means for heating said sole plate and the water in said boiler to produce steam.

3. A steam and dampening iron comprising a sole plate, a steam boiler for the reception of steam and water and having a steam space and water space, an atomizing device comprising a water conductor having one end extending into said water space and the other end extending above the sole plate exteriorly of said boiler and provided with an atomizing discharge outlet for conducting the atomized water to the material to be ironed, said atomizing discharge outlet extending above said sole plate so that the atomized water can burst into a cloud of atomized water before contacting the material to be ironed, to properly dampen the material, steam conducting means communicating with said steam space and with an

opening through said sole plate for conducting steam to the material to be ironed and valve control means communicating with said water and steam conducting means for directing the water through said atomizing discharge outlet to the material to be ironed for dampening the material, and for directing the steam through said sole plate opening for steaming the material, and means for heating said sole plate and the water in said boiler to produce steam.

- 10 5 4. A dampening and pressing iron comprising a sole plate, a boiler for the reception of steam and water, said boiler having a steam space and a water space, an atomizing device comprising a water conductor having one end extending into said water space and the other end 15 extending above said sole plate exteriorly of said boiler for conducting atomized water from said boiler to the material to be ironed so that the atomized water will scatter over the material in a cloud of atomized water, at least a part of said conductor being restricted to enable 20 the steam pressure within the boiler to effect atomization of the water passing through said conductor and a valve in the passageway of said conductor for controlling the atomized water, and means for heating said sole plate and the water in said boiler to produce steam.
